CLAIM

The ornamental design for a barrel for collecting and dispensing rainwater, as shown and described.

DESCRIPTION

FIG. 1 is a front elevational view of a barrel for collecting and dispensing rainwater showing our new design; FIG. 2 is a right side elevational view thereof; FIG. 3 is a rear elevational view thereof; FIG. 4 is a top plan view thereof; and, FIG. 5 is a bottom plan view thereof.

The broken line showing of environmental structure in FIGS. 2 and 4 is for illustrative purposes only and does not form part of the claimed design.

FIG. 4

FIG. 1

FIG. 2

FIG. 5

FIG. 3
